CLAIM

[21] Appl. No.: 861,493

The ornamental design for a combined bezel and wall switch actuators, as shown and described.

[22] Filed: Mar. 31, 1992

DESCRIPTION

[52] U.S. Cl. D13/169; D13/171
[58] Field of Search D13/158, 162, 164, 169,
D13/170; D8/353; 220/3.8, 241; 338/197;
200/1 R, 310, 317, 339, 547, 553

FIG. 1 is a perspective view of combined bezel and wall switch actuators in accordance with the invention;
FIG. 2 is a front elevational of the FIG. 1 design;
FIG. 3 is a top plan view of the FIG. 1 design;
FIG. 4 is a left side elevational view of the FIG. 1 design;
FIG. 5 is a right side elevational view of the FIG. 1 design; and,
FIG. 6 is a bottom plan view of the FIG. 1 design.
